UNITED STATES PATENT OFFICE.

GEORGE W. GOETSCH, OF ELKINS PARK, PENNSYLVANIA, ASSIGNOR TO QUAKER HOSIERY COMPANY, OF PHILADELPHIA, PENNSYLVANIA, A CORPORATION OF PENNSYLVANIA.

DESIGN FOR A STOCKING.

Application filed August 6, 1928. Serial No. 27,724. Term of patent 14 years.

To all whom it may concern:

Be it known that I, GEORGE W. GOETSCH, a citizen of the United States of America, residing at Elkins Park, in the county of Montgomery and State of Pennsylvania, have invented a new, original, and ornamental Design for Stockings, of which the following is a specification, reference being had to the accompanying drawing, forming part thereof.

Fig. I is a side elevation of a stocking showing my new design; and,

Fig. II is a rear view of the ankle portion of the stocking.

I claim:

The ornamental design for a stocking, as

GEORGE W. GOETSCH.
